UNITED STATES PATENT OFFICE.

EDWIN H. POTTER, OF BROOKLYN, NEW YORK, AND CHARLES S. SHARP, OF BOONTON, NEW JERSEY, ASSIGNEES TO HUBBARD OVEN AND MFG. CO., INC., OF CHICAGO, ILLINOIS, A CORPORATION OF ILLINOIS.

GAS-BURNER STRUCTURE FOR BAKERS' OVENS.

Application filed July 3, 1925. Serial No. 41,245.

This invention relates, generally, to improvements in bakers' ovens provided with gas burners as the source of heat.

Our invention has for its principal object to provide a novel construction and arrangement of combustion chamber beneath the oven bed shelf, in which are disposed gas burners of the pipe type, adapted to extend, preferably, from the front of the oven approximately throughout its entire depth, together with a novel construction and arrangement of means for so supplying air to the burners to support combustion of the gas delivered therefrom, that uniform and complete combustion of such gas throughout the entire lengths of the burners is assured, and consequently a uniform and properly diffused heat is produced without waste or odor, and without the production of dirt, soot or similar undesirable effects of incomplete or irregular combustion.

Another object of this invention is to provide a novel means for insuring the initial ignition of the gas burners throughout their entire length whenever gas is delivered to and through the same.

Other objects of this invention, not at this time more particularly enumerated, will be clearly understood from the following detailed description of the same.

The invention is clearly illustrated in the accompanying drawings, in which:

Figure 1 is a partial front elevation of a baker's oven provided with gas burners and constructed in accordance with the principles of our invention; Figure 2 is a fragmentary vertical transverse section, taken on line 2—2 in Figure 1, but drawn on an enlarged scale; Figure 3 is a fragmentary detail vertical longitudinal section, taken on line 3—3 in Figure 2, but drawn on a further enlarged scale; Figure 4 is a fragmentary vertical transverse section, taken on line 4—4 in Figure 3; Figure 5 is a fragmentary bottom plan view of a burner baffle; and Figure 6 is a similar view showing a modified construction of said burner baffle.

Similar characters of reference are employed in all of the hereinabove described views, to indicate corresponding parts.

Referring now to said drawings, the reference character 1 indicates the complete baker's oven made according to and embodying

the principles of our present invention. In its general features of construction the oven consists of a main housing comprising outer enclosing walls 2, preferably of the double or hollow type, the interior spaces of which are packed with mineral wool 3, to provide heat insulation, or any other suitable or well known construction may be employed. The interior of the main housing is suitably subdivided by tile walls, such as the tile bed-shelf 4 shown in Figure 2, to provide in the upper portion thereof the oven proper or baking chamber 5. The space within said main housing, which is beneath said bed-shelf 4, provides a combustion chamber 6. Said combustion chamber space is further subdivided by a horizontal partition or false-bottom 7, spaced above the true bottom 8 of the housing, so as to provide, coextensive with and beneath the combustion chamber 6, an air-box or intake chamber 9. The enclosing wall 2 is pierced with openings 10 leading into said air-box or intake chamber 9.

The reference character 11 indicates the gas burners of the oven, the same being of the pipe type; that is, being formed from suitable lengths of pipe provided at their upper faces with burner perforations 12, which are spaced apart to provide a longitudinally disposed row from end to end of each burner. Said burners 11 are suitably supported above the partition or false bottom 7, so as to extend from front to rear across the bottom of the combustion chamber 6, the same being laterally spaced apart at desired intervals.

The reference character 13 indicates a main gas supply pipe which extends exteriorly across the lower front of the oven structure. Each gas burner 11 is connected in communication with said supply pipe 13 by suitable feed connections 14, which extend through the outer wall 2 into coupled relation with each burner. Each feed connection 14 may be provided with an air-mixing fixture 15, and may be further provided with a shut-off valve 16, so that the supply of gas to the burners may be individually and selectively controlled. Said main gas supply pipe 13 is provided with a main gas-cock or shut-off valve 17 to generally control the supply of gas to the burners.

The only connection the combustion chamber has with atmospheric air is through air delivery ports 18 which are provided in the partition or false bottom 7 intermediate the 5 combustion chamber 6 and the air-box or intake chamber 9, to extend longitudinally beneath, and, preferably along each side of each burner 11. Secured to the upper side of said partition or false bottom 7, to extend 10 respectively adjacent to each side of each burner 11 and above the air delivery ports 18, are inclined deflector flanges 19 which are respectively inclined toward each other so as to tend to converge above the burners 11, 15 but with their free edges spaced laterally apart to provide an open combustion space 20 above the burner perforations 12.

Arranged to extend transversely beneath and adjacent to the forward ends of the 20 burners 11 is a pilot or ignition burner 21 provided with burner openings 22 adjacent to each burner 11, to thereby furnish a pilot or ignition flame adjacent to each burner 11. Said pilot burner 21 is interconnected with said main gas supply pipe 13 by a suitable feed connection 23, including a shut-off valve 24.

Supported in longitudinal extension above each pipe burner 11, so as to be suitably 30 spaced above and coincident to the row of burner perforations 12 is a baffle-plate 25. The means for adjustably supporting each baffle-plate 25 comprises a series of spaced pairs of standards 26, the members of which are suitably affixed to the partition or false bottom 7 to respectively project upwardly on opposite sides of the burner 11. The free ends of said standards are threaded to receive supporting nuts 27. The baffle-plate 25 35 is provided, at spaced intervals corresponding to the spacing of said pairs of standards 26, with transverse bridge pieces 28, the free ends of which are perforated to pass over said standards so as to be mutually supported by said supporting nuts 27. Lock nuts 29 are provided on each standard above the engaged ends of said bridge pieces 28 to secure the latter against removal from said supporting nuts. It will be understood from the 40 above description, and from an inspection of the accompanying drawings, that the elevation of the baffle plates 25 above the burners 11 may be regulated or adjusted, by raising or lowering the supporting nuts 27 as 45 may be desired, and that said baffle-plates 25 may therefore be positioned at proper heights above the burner perforations 13 according to the height of the flame issuing 50 therefrom. The undersides of said baffle-plates 25 are provided with transverse suitably spaced scores or grooves 30 of a depth 55 preferably approximating one-half of the thickness of the baffle-plates. These scores 60 may be directly transverse, that is at right angles to the longitude of the baffle-plate, as

shown in Figure 5, or the same may be diagonally transverse, as shown in Figure 6. The said scores or grooves 30 are close enough to each other so that expansion of the portions of said baffle-plates immediately exposed to burner flames takes place in each short intermediate section, and is not carried throughout the entire baffle plate. As will be evident said baffle plates are removable for replacement or repair as occasion 75 may require.

The operation of the novel construction of gas burner arrangement above described, with the attendant advantages, is as follows:—

Either natural or manufactured gas may be supplied to the burners 11; and the latter may be either of the atmospheric type, as shown, or of the pre-mixed type.

Gas is delivered in required volume to the 85 pilot burner 21 by manipulating the control valve 24, so that, after initial ignition of the same, a pilot flame is provided adjacent to the forward end of each burner 11.

The gas may be delivered through the 90 main supply pipe 13 by opening the main control valve 17, and the delivery of gas to the respective burners 11 may be selectively controlled by manipulating the individual 95 shut-off valves 16 with which each burner is provided.

When gas is thus delivered to any one or more of the burners 11, the same will issue 100 from the burner perforations 12, and will accumulate beneath the baffle plate 25, whereupon the adjacent pilot flame will ignite the gas, so that an igniting flame will progress beneath the baffle plate throughout the entire length of the burner 11, thus assuring complete ignition of the gas issuing 105 from the burner perforations 12 from one end of the burner 11 to the other.

Since the only communication which the combustion chamber 6 possesses with the outside atmosphere is by way of the air-box or intake chamber 9 through the air ports 18 in the partition or false bottom 7 (said air-box or intake receiving the air through the intake ports 10), it follows that air to provide oxygen to support the combustion of 110 gas at the burners 11 is evenly distributed through said air ports 18 beneath said burners and throughout the entire length of the latter, without regard to the temperature 115 inside the combustion chamber 6, in other words, without interference due to back pressures produced by the hot gases circulated within the combustion chamber. The advantage of even and continuous delivery of 120 fresh air at the points of gas combustion throughout the length of the burners 11, is further enhanced and assured by reason of the provision of the inwardly and upwardly inclined deflector flanges 19 disposed along 125 each side of each burner, since these deflector 130

flanges tend not only to cause an upward draft of air through the air ports 18, but also tend to deflect or direct the incoming air toward the points of combustion of the gas issuing from the burner openings 12, thereby assuring both a continuous flow of air from the air box 9 in sufficient volume to assure complete combustion of the gas issuing from the burners at all points throughout the length of the latter, as well as a proper delivery of such air to the zone of combustion above each burner. Another advantage of the described arrangement of deflector flanges 19 is that the same tend to retard the admission of air through the air ports 18 beneath burners which are not in use, since the heated condition of the combustion chamber tends to repel air from entering the combustion chamber in the absence of the draft induced by combustion of gas above the burner.

From the above description of the construction and operation of our novel gas burner arrangement for bakers' ovens, it will be understood that a maximum efficiency is obtained from each burner through the provision of means whereby sufficient air is delivered in support of combustion throughout the entire length of each burner, thus assuring even and complete combustion of gas throughout the entire interior of the combustion chamber, and a consequent uniform application of the resultant heat to and around the baking chamber 6.

We are aware that some changes may be made in the general arrangements and combinations of the various devices and parts of our novel gas burner arrangement for bakers' ovens, as well as in the details of the construction of the same, without departing from the scope of our present invention as described in the foregoing specification, and as defined in the appended claims. Hence, we do not limit our invention to the exact arrangements and combinations of the devices and parts as set forth in the foregoing specification, nor do we confine ourselves to the exact details of the construction of said parts as illustrated in the accompanying drawings.

We claim:

1. The combination with a baker's oven provided with a baking chamber and adjacent combustion chamber of a partition means subdividing said combustion chamber to form an underlying air box having air intake ports communicating directly with the outer atmosphere, a plurality of perforated pipe gas burners within said combustion chamber above said partition means, means for supplying gas to said burners, said partition means having air delivery ports leading from said air box coincident to and beneath each burner, and inwardly and upwardly inclined deflector plates above said

air delivery ports and arranged to overhang the sides of each burner for the purposes described.

2. The combination with a baker's oven provided with a baking chamber and adjacent combustion chamber of a partition means subdividing said combustion chamber to form an underlying air box having air intake ports communicating directly with the outer atmosphere, a plurality of perforated pipe gas burners within said combustion chamber above said partition means, means for supplying gas to said burners, said partition means having air delivery ports leading from said air box coincident to and beneath each burner, inwardly and upwardly inclined deflector plates above said air delivery ports and arranged to overhang the sides of each burner, and a baffle plate spaced above and longitudinally coextensive with each burner.

3. The combination with a baker's oven provided with a baking chamber and adjacent combustion chamber of a partition means subdividing said combustion chamber to form an underlying air box having air intake ports communicating directly with the outer atmosphere, a plurality of perforated pipe gas burners within said combustion chamber above said partition means, means for supplying gas to said burners, said partition means having air delivery ports leading from said air box coincident to and beneath each burner, inwardly and upwardly inclined deflector plates above said air delivery ports and arranged to overhang the sides of each burner, a baffle plate spaced above and longitudinally coextensive with each burner, and means for adjustably and removably supporting said baffle-plates.

4. The combination with a baker's oven provided with a baking chamber and adjacent combustion chamber of a partition means subdividing said combustion chamber to form an underlying air box having air intake ports communicating directly with the outer atmosphere, a plurality of perforated pipe gas burners within said combustion chamber above said partition means, means for supplying gas to said burners, said partition means having air delivery ports leading from said air box coincident to and beneath each burner, inwardly and upwardly inclined deflector plates above said delivery ports and arranged to overhang the sides of each burner, a baffle plate spaced above and longitudinally coextensive with each burner, and each baffle-plate having at its under or burner facing side expansion compensating means comprising a plurality of spaced apart transverse channels.

5. The combination with a baker's oven provided with a baking chamber and adjacent combustion chamber of a partition means subdividing said combustion chamber

- means subdividing said combustion chamber to form an underlying air box having air intake ports communicating directly with the outer atmosphere, a plurality of perforated pipe gas burners within said combustion chamber above said partition means, said partition means having air delivery ports leading from said air box coincident to and beneath each burner, inwardly and upwardly inclined deflector plates above said air delivery ports and arranged to overhang the sides of each burner, a pilot burner to provide an ignition flame adjacent to each pipe burner, means for supplying gas to said pipe burners and to said pilot burner, a baffle-plate spaced above and longitudinally coextensive with each burner, and each baffle-plate having at its under or burner facing side expansion compensating means comprising a plurality of spaced apart transverse channels.

12. A gas burner structure for ovens or the like having a combustion chamber, comprising an air box beneath the bottom of said combustion chamber, a perforate pipe gas burner extending across the bottom of said combustion chamber, said combustion chamber bottom having air delivery means leading from said air box coincident to and beneath said gas burner, and inwardly and upwardly inclined deflector plates above said air delivery means arranged to overhang the sides of said gas burner.

13. A gas burner structure for ovens or

the like having a combustion chamber, comprising an air box beneath the bottom of said combustion chamber, a perforate pipe gas burner extending across the bottom of said combustion chamber, said combustion chamber bottom having air delivery means leading from said air box coincident to and beneath said gas burner, inwardly and upwardly inclined deflector plates above said air delivery means arranged to overhang the sides of said gas burner and a baffle plate spaced above and longitudinally coextensive with said gas burner.

14. The combination with a perforate pipe gas burner of a baffle plate spaced above and longitudinally coextensive with said burner, means for adjustably and removably supporting said baffle plate, and said baffle plate having at its under or burner facing side expansion compensating means comprising a plurality of spaced apart transverse channels.

15. The combination with a perforate pipe gas burner of a baffle plate spaced above and longitudinally coextensive with said burner, said baffle plate having at its under or burner facing side expansion compensating means comprising a plurality of spaced apart transverse channels.

In testimony that we claim the invention set forth above we have hereunto set our hands this 8th day of June, 1925.

EDWIN H. POTTER.
CHARLES S. SHARP.
